(57) CLAIM

The ornamental design for a Halloween pumpkin punch out kit, as shown.

DESCRIPTION

FIG. 1 is a front elevational view of a Halloween pumpkin punch out kit showing our new design; and,

FIG. 2 is a front elevational of the lettering included in the Halloween pumpkin punch out kit depicted in FIG. 1.

All surfaces not shown form no part of the claimed design.

A back view of the Halloween pumpkin punch out kit is being omitted since it is an identical/mirror image of the front view and contains no ornamentality.
